UNITED STATES PATENT OFFICE.

HARRISON G. SLOANE, OF SAN DIEGO, CALIFORNIA.

HAT AND PARCEL CARRIER.

Application filed July 31, 1923. Serial No. 654,911.

It is the object of my invention to provide a novel means for carrying hats and light parcels in a convenient position immediately below the roof of an automobile top, Pullman berth or other compartment, so constructed as to be quickly attached or detached, to be collapsed or portable when not in use and to be accessible, in use, either from the front or rear without adjustment of buckles or other fastenings.

I attain this object, through one form of construction, by the mechanism illustrated in the accompanying drawings, in which Figure 1 is a top plan; Figure 2 a partial side elevation through 2—2; Figure 3 a detail of section through 3—3; Figure 4 is a detail of one means for attaching the carrier to the top bows of an automobile. In Figures 2 and 3 the dotted lines indicate the position which the mechanism takes when it is lowered or opened for the purpose of receiving any article.

Like characters of reference refer to similar parts and portions throughout the several views.

Referring to the accompanying drawings, I provide a shallow bag or basket 2, constructed of net, canvas or other suitable material. Preferably, this consists of a flat rectangular bottom with narrow upturned edges. The ends 1, of the carrier may consist of wooden slats or other rigid material, supplying a portion of the upturned edge and at the same time furnishing a convenient base for attaching the suspending springs 3. Other spreader members 11, may be used at intervals, serving to prevent sagging of the basket and also giving a connecting point on the upturned ends thereof, at 40 which auxiliary springs 12, may be attached, if desired.

Suspending springs 3, are attached near the corners of the carrier in such manner as to extend horizontally toward the adjacent rounded corners of the top bows. They may be connected directly from screw-eyes in the sides 1, to screw-eyes in the top bows, but I prefer to supply adjustable and detachable connections. To that end, on the drawings shown, slots or holes 13, are located in the end pieces 1. Straps or short pieces of light chain 5, are inserted through certain of the holes 13, near the extremities of the end pieces. Buttons 4, at the ends of the chains are held snug against the insides of the end pieces. By use of different pairs of

the holes 13, the distance between the supporting springs can be made wider or narrower to accommodate the carrier to different styles of automobile tops. One end of 60 each spring 3, is formed into a hook 6, which engages any link of the chain 5, thereby giving a longer or shorter connection between the carrier and the top bow. This feature serves to accommodate the carrier to 65 automobile tops of different widths and also permits regulation of the tension of the springs. The free, or unused end of the chain 5, may be looped through the spring as shown in the drawing. The other end of 70 the spring 3, is formed into a hook 7, which engages a ring or eyelet 8.

For convenience in installing the carrier in automobiles, I prefer to supply a strap or thong as shown in Figure 4. This consists 75 of a flexible strip of leather or other material with a ring 8, fixed at one end and a loop 10, formed at the other. To supply a convenient suspension point, the strap is placed around the top bow, preferably high 80 up on the rounded corner of the bow, and the ring end 8, is slipped through the loop end 10, and is drawn tight. The ring 8, is then in proper position for engaging the hook 7, of the suspending spring.

The manner of suspension described gives a resilient carrier which conforms itself to the bulk of any article placed within it. In its normal position it hangs flat and close under the roof of the top. By pulling down 90 on either the front or rear edge with a slight pressure, the springs allow such edge to drop so that articles may be easily inserted or extracted. Upon being released the carrier immediately resumes its normal position 95 through contraction of the springs.

Some degree of resiliency and like access to the carrier may be provided by variations in the mechanism illustrated; for example, the substitution of taut straps in the place 100 of the horizontal springs and connecting members; such straps extending directly to the supporting points or crossing in X fashion. By the latter means, or by use of a fixed pivotal support at some point on the end pieces 1, the tilting effect supplied by the springs may be reproduced. Likewise a spring or elastic element may be inserted at some point other than near the extremities of the strain bearing members. I do not desire, therefore, to limit my invention to the 105 precise mechanism described but intend to 110

claim broadly any structure which will accomplish the same functions.

What I claim is:

1. In a hat and parcel carrier, a substantially flat surfaced main supporting member, a substantially flat rack member positioned with one side in close proximity to said main supporting member, and elastic means tending to hold said rack member in close relation to said main supporting member but yieldable for placing articles between said rack member and said main supporting member.
  2. In a carrier of the class described, a main supporting member, a substantially flat straight rack member yieldably suspended thereon adapted to be depressed from said supporting member to permit the placing of articles between said supporting member and said rack member, and engage and hold said articles when released.
  3. In a carrier of the class described, a main supporting means, a substantially flat straight, rigid rack member supported thereon, an elastic means supporting said rack yieldable relatively to said main supporting means to permit the placing, holding and removal of packages between said rack member and said main support.
  4. In a carrier of the class described, the combination with a vehicle top and the bows for supporting said top, of a substantially flat rigid rack member with one flat side positioned in close proximity to the lower surface of the top, and elastic means between said bows of said top and said rack, whereby said rack is suspended on said bows
- in close proximity to said top adapted to permit said rack to be forced downwardly for placing bundles between said rack and said top, and when released press said members between said rack and said top.
5. In a carrier of the class described, a main supporting means, and a basket like rack resiliently suspended adjacent to and parallel with said support, whereby said rack may be quickly forced away from said support for placing articles in said rack.
6. In a carrier of the class described, a main, substantially flat surfaced supporting means, and a substantially flat bottomed rack resiliently suspended adjacent to and parallel with said support whereby said rack may be quickly forced away from said support for placing articles in said rack and yieldably supporting said rack relatively to said support.
7. In a carrier of the class described, a main flat surfaced supporting means, and a rack resiliently suspended adjacent to and parallel with said main flat surfaced supporting means, whereby said rack may be quickly forced away from said support for placing articles on said rack.
8. In a carrier of the class described, the combination with a vehicle top of straps looped around pairs of bows of the top and adapted to be shifted to varying positions thereon, resilient members secured to said straps, and a relatively flat bottomed rack member suspended on said resilient members.

HARRISON G. SLOANE.
